(57) **CLAIM**

I claim the ornamental design for a cylindrical carrying case, as shown and described.

DESCRIPTION

FIG. 1 is a side perspective view of a cylindrical carrying case;

FIG. 2 is a front view of FIG. 1;

FIG. 3 is a rear view of FIG. 1;

FIG. 4 is a left side view of FIG. 2; and,

FIG. 5 is a right side view of FIG. 2.

The broken lines represent the stitch lines. Other broken lines showing of zipper pull is for illustrative purpose only and form no part of the claimed design.

1 Claim, 5 Drawing Sheets

FIG. 1

FIG. 2

FIG. 3

FIG. 4

FIG. 5
